UNITED STATES PATENT OFFICE.

THOMAS J. MITCHELL AND JAMES A. McCREARY, OF UNIONTOWN, PENNSYLVANIA.

TROLLEY MECHANISM FOR COKE-OVEN DOORS.

1,181,472.

Specification of Letters Patent. Patented May 2, 1916.

Original application filed October 25, 1910, Serial No. 589,061. Divided and this application filed July 18, 1912. Serial No. 710,303.

To all whom it may concern:

Be it known that we, THOMAS J. MITCHELL and JAMES A. McCREARY, citizens of the United States, residing at Uniontown, in the county of Fayette, State of Pennsylvania, have invented a new and useful Trolley Mechanism for Coke-Oven Doors, of which the following is a specification.

This invention relates to an improvement 10 in trolley mechanism for coke oven door.

The primary object of the invention is to provide means, movable longitudinally of the battery of ovens and which may be attached to the oven door, in placing the same 15 in position and removing the door from one oven to another.

A further object of the invention is to provide a construction in which the member which engages the oven door, may be adjusted to compensate for the irregularity of 20 the oven wall or contraction of the door.

With the foregoing and other objects in view which will appear as the description proceeds, the invention resides in the combination and arrangement of the parts hereinafter described and claimed, it being understood that changes in the precise embodiment of invention herein disclosed can be made within the scope of what is claimed 25 without departing from the spirit of the invention.

In the accompanying drawing, Figure 1 is a view in elevation showing two ovens, one of the doors being shown about to be positioned within the door opening, the other door being shown in position within 30 the opening. Fig. 2 is a detail view of the trolley mechanism. Fig. 3 is a detail view of the nut. Fig. 4 is a sectional view of a 35 portion of a coke oven, showing the door and its supporting mechanism in end elevation.

In the drawing 10, designates the ovens, which may be of any type and which are 40 formed with the door openings 11. In both the rectangular and beehive type of oven it has been found that a hinged door cannot be maintained snugly within the door opening of the oven after the oven has been fired 45 several times. This is due to the expansion and contraction of the material of which the oven is formed and the fact that when the door is hinged, the same must be presented to the door opening at exactly the 50 same point, regardless of any irregularity 55

of the oven wall caused by heat. It will thus be noted that should the wall of the oven contract to any great extent and the hinged door be swung in position, the door will assume its original position with respect to the oven, as though the tile had not contracted and regardless of the position of the door opening or of the fact that the front wall of the oven may have become distorted by heat. It is therefore essential that means be provided whereby the door may be presented to the opening of the oven to close the same regardless of the degree of shrinkage of the oven wall. In the present invention the proper positioning of the door is secured by suspending the same from a trolley disposed longitudinally of the battery of ovens. Thus the door being supported independently of the oven may be swung into proper position with respect to the oven regardless of the degree of contraction of the oven wall, the door opening, being beveled as indicated at *a*, and the edges of the tile of which the door is formed, having a corresponding bevel as at *b* toward their fire faces assuring a snug fit, air being excluded when the loam or mud, is placed around the edges of the door. It has heretofore been the practice to support the hinge mechanism by bolting through the front wall of the oven at the side of the opening; the securing devices thus being subjected to great heat after the continued use of the oven, are burnt out causing the hinge mechanism to become displaced. The ovens of 60 what is known in the trade as the "Mitchell type" are provided with the front wall 12, which rises above the crown of the oven and the present invention contemplates providing a structure arranged to embrace the extended front wall, to support the trolley mechanism, the same being positioned at a point where heat will not affect the same.

The bracket member 14, is provided with an angle iron 15 which supports the track 16 of the trolley and is formed with the wall engaging extension 17, the terminal 18 of which is offset to embrace the rear face of the front wall of the oven; the bracket supporting track 16 in this manner is supported without its supporting member being subjected to intense heat, the extended wall of the oven above the crown not being heated to an extent where the same will injure the metal above the lines A—B. The trolley 100 105 110

ley wheel 19 is flanged and disposed for a pivotal movement on the track 16, the straps 20 which are supported on the shaft 21 on which the trolley wheel is mounted being connected at the points 22 the bolt 24 which passes through the offset terminal 25 of said strap, extending through the terminals 26 of the hanger 27. An eye bolt 28 passes through the base portion 29 of said hanger, 10 a nut 30 receiving said eye bolt, said nut being formed with the reduced portion 31 which is seated within the portion 29 of the hanger, the eye bolt being rotated to raise and lower the door engaging member 33 15 which is supported by this eye bolt, this door lifting member, consisting of the rod 34, the terminal of which is given a compound or S shaped curve, the looped portion 35 embracing the eye of the eye bolt 28, 20 and the looped terminal 36 being arranged to engage in the loop 37 of the door frame.

It will be noted by this construction that the door when suspended from the looped terminal 36 of the lever may be moved on 25 the beam 16, the terminal 38 of the lever 33 being held by the hook 39 carried by the door and disposed directly beneath the loop 37. The lever in this manner is supported against swinging movement, the contact of 30 the lower portion of the lever with the hook 39 retaining the looped terminal 36 in engagement with the bail 37 which supports or carries the door frame. It will be noted that the lever is adjusted vertically with 35 respect to the hanger 27, therefore if the door, due to contraction of the door or oven wall which is caused by the heat of the oven should be out of adjustment with the curved terminal 36 of the lever 34, the lever may 40 be raised or lowered to a position where the same may engage the bail 37. In removing the door the trolley is brought to a position where the lever 33 alines with the bail 37. The lever is then raised, its curved terminal 45 33 being placed within the bail 37. The lever is then brought to a vertical position, the same being fulcrumed in this movement at the point 40, this movement raising the door out of the door opening. The terminal 50 38 of the lever is then placed within the hook 39 and the door may be moved along the rail 16 to a point adjacent the oven.

The present invention also includes a further feature of practical importance, with 55 respect to which the present application is a division of a parent application Ser. No. 589,061, filed October 25, 1910. That is the carrier device or trolley mechanism is adapted to lift and shift the entire door, as 60 shown in the drawings, or to lift and shift simply the upper section of the door alone, which becomes necessary in leveling and watering operations of the oven. This is provided for by a separable locking or 65 latching connection between the two door

sections, suitable latches or locks for that purpose being designated by the reference letter L in the drawings.

The many advantages of a trolley mechanism of this character will be clearly apparent, as it will be noted that the same may be readily brought into door engaging position. It will also be noted that the supporting mechanism for the trolley is such that it may be readily positioned on the oven, 75 and that it is so positioned on the oven that the same is not affected by the heat.

As herein indicated, a distinctive and important feature of the invention resides in the beveling of the oven door and the corresponding sides of the door opening so that when the beveled door is adjusted to the beveled opening it requires very little mud or cement sealing to exclude the air. This is a very important consideration in 85 coke oven doors. Furthermore, by so beveling the edges of the door the center of gravity of the door is thrown inwardly and tends to hold the door closed. To facilitate the opening of such a door it is necessary 90 not only to pull it upwardly but also outwardly, and therefore, it is desirable to locate the trolley forwardly of the door. This provides an important and practical combination of features in a coke oven door construction.

Another feature of practical importance in carrying out the invention resides in having the door of a horizontally divided type, the same consisting of separate upper and 100 lower mating door sections A and B, and which door sections are adapted to be temporarily locked together by a suitable latching or fastening means such as the hook devices C shown in the drawings. Accordingly, the present invention also involves the sectional door with means for moving it horizontally, together with means for temporarily locking the sections together, so that by a single means the entire door or 110 only the upper door section may be shifted.

What is claimed is:

1. The combination with a coke-oven having a removable door provided with a loop on its crest and an overhead trolley device 115 having a hanger provided with a terminal eye movable adjacent the said loop, of a lever having an angular S-shaped portion at one end, the inner bend of the said S-shaped portion engaging through the said 120 hanger eye, and the outer bend of the said S-shaped portion being formed with a hook for engagement through the said loop, and interengageable means carried by the other end of the lever and the door.

2. A coke oven having an inclined front wall and an opening therein having beveled edges, a door having beveled edges to fit said opening, whereby the weight of the door tends to hold the door closed, and 125 130

means located above and forwardly of said opening to raise and pull open the door.

3. A coke oven having a beveled door opening, a horizontally divided door beveled to fit said opening consisting of separate upper and lower mating sections, the upper section being shiftable horizontally independently of the lower section, and a door shifting device together with means for temporarily locking the two sections together.

4. A coke oven provided with a door opening having a beveled seat extending entirely about the same, a coke oven door provided with a body of refractory material having a beveled edge portion fitting in the beveled seat of the door opening in direct contact with the masonry faces thereof, and a door lifting and shifting device supported beyond the plane of the door opening and having a connection with the door for lifting and pulling the same forward.

5. The combination with a trolley and a track member for supporting the same, of an adjustable bearing member connected to the trolley, and a door lifting member fulcrumed upon said bearing member and including an upper door engaging terminal extended substantially horizontally, and a depending terminal, said depending terminal and the adjustable member being supported directly under the track member.

6. The combination with a trolley and a track member for supporting the same, of a threaded element adjustably engaging the trolley, a rod having a looped bearing portion for engaging said bearing element, there being a substantially horizontally extending crooked door engaging arm at the upper end of the rod and a depending arm formed by the lower portion of the rod.

7. The combination with a trolley and a track member for supporting the same, of a bearing element adjustably engaging the

trolley, a rod having a looped bearing portion for engaging said bearing element, there being a substantially horizontally extending crooked door engaging arm at the upper end of the rod and a depending arm formed by the lower portion of the rod, 50 said depending portion and the adjustable element being supported directly under the track member.

8. The combination with a track member, of a trolley including downwardly converging straps, said track member being extended therebetween, and a hanger depending from the straps and directly under the track member, of a vertically adjustable bearing member supported by the hanger and directly under the track member, and a door lifting member fulcrumed upon said bearing member and including an upper door engaging terminal normally extended substantially horizontally, and a depending terminal.

9. The combination with a track member, of a trolley including downwardly converging straps, said track member being extended therebetween, and a hanger depending from the straps and directly under the track member, of a vertically adjustable bearing member supported by the hanger and directly under the track member, a door lifting member fulcrumed upon said bearing member and including an upper door engaging terminal normally extended substantially horizontally, a depending terminal, and means for engaging said depending terminal to hold it against oscillation.

In testimony that we claim the foregoing as our own, we have hereunto affixed our signatures in the presence of two witnesses.
